CLAIM

The ornamental design for a frame for telephone wire terminal blocks, as shown and described.

DESCRIPTION

FIG. 1 is a front elevational view of a frame for telephone wire terminal blocks showing our new design;

FIG. 2 is a top plan view thereof;

FIG. 3 is a bottom plan view thereof;

FIG. 4 is a rear elevational view thereof;

FIG. 5 is a left side elevational view thereof, the opposite side being a mirror image;

FIG. 6 is a cross-sectional view taken along the line 6—6 in FIG. 4; and,

FIG. 7 is a fragmentary front, bottom and right side enlarged perspective view thereof.

FIG. 1

FIG. 2

FIG. 3

FIG. 4

FIG. 5

FIG. 6

FIG. 7
